[57] CLAIM

The ornamental design for an eyeglass case, as shown
and described.

DESCRIPTION

FIG. 1 is a front elevational view of an eyeglass case
showing my new design;

FIG. 2 is a right side elevational view;

FIG. 3 is a rear elevational view;

FIG. 4 is a top plan view;

FIG. 5 is a bottom plan view;

FIG. 6 is a front elevational view with the front flap
open.

FIG. 7 is a vertical cross-sectional view taken through
the center of the eyeglass case; and

FIG. 8 is a perspective view.
